DESIGN FOR A RUG

George E. Mallinson, Amityville, N. Y.

Application October 15, 1937, Serial No. 72,196

Term of patent 3½ years

To all whom it may concern:

Be it known that I, George E. Mallinson, a citizen of the United States, residing at Amityville, county of Suffolk, and State of New York, have invented a new, original, and ornamental Design for a Rug, of which the following is a specification, reference being had to the accompanying drawing, forming part thereof, wherein—

The figure is a plan view of a rug embodying my new design. The drawing is of a complete rug except for the omission of fringe along the upper edge of the figure similar to the fringe shown at the lower edge thereof.

I claim:

The ornamental design for a rug substantially as shown.

GEORGE E. MALLINSON.
